CONTAINER FOR SPOOLS OF CORD

Alfred E. Bogren, Milford, N.J., assignor to Continental Can Company, Inc., New York, N.Y., a corporation of New York

Filed Jan. 6, 1964, Ser. No. 335,756
5 Claims. (Cl. 229—51)

This invention relates to a unitized package comprising a plurality of containers and more particularly relates to a corrugated, dual container for the packaging of spools of cord of the type used in modern baling machines.

In modern automatic baling machines it is customary to use at least two balls of baling twine or cord. While one of the balls of twine is being used, the other ball of twine constitutes a reserve supply. These balls have usually been tied together by attaching the trailing end of the first ball to the leading end of the second ball. In order to reduce the possibility of the ball of twine collapsing and becoming tangled, it has previously been customary to wrap the ball of twine with a layer of wrapping paper. Quite frequently, this paper becomes damaged or is simply inadequate to suitably support the ball of twine.

It is an object of the present invention to provide a container for baling twine or cord, which container is more suitable than those previously known and which is particularly adapted for packaging a pair of balls of twine.

Another object of this invention is to provide a unitized package comprising a plurality of containers and a pair of closure caps therefor, each of the containers including a tubular member with each tubular member being open at each end thereof, and a closure cap at each end of the tubular member for closing adjacent containers and connecting the containers into a single unit.

Another object of this invention is to provide a novel closure cap which is adapted to cover an adjacent pair of containers, said cap comprising a first cover section and a second cover section, the first cover section and the second cover section being joined along a transverse center line, means attached to the closure cap along the periphery thereof for connecting the closure cap to the containers, and a removable section which extends on opposite sides of the transverse center line and is adapted to be torn from the closure cap such that the adjacent pair of containers are separated from each other.

Another object of this invention is to provide a closure cap, of the type described above, wherein the removable section has opposite ends thereof which are located adjacent to the geometrical center of each of the cover sections, the opposite ends being defined by cut lines and the removable section being further defined by weakening lines which diverge from each cut line and meet at the transverse center line.

Another object of this invention is to provide a closure cap of the type described above wherein a reinforcing tape extends on opposite sides of the transverse center line, and the tape includes a plurality of fibers which extend diagonally of the transverse center line in at least two directions whereby the reinforcing tape is unlikely to rupture along the transverse center line.

Another object of this invention is to provide a pair of containers and a pair of closure caps forming a package which is particularly adapted to be used with balls of baling twine, the containers each being comprised of an upright tubular member adapted to receive a ball of twine, each of the closure caps being comprised of a pair of cover sections for closing the tubular members, the cover sections being symmetrical about and joined together along a transverse center line at a reduced por-

2

tion of the respective closure cap, each of the closure caps having a removable section thereof which extends on opposite sides of the transverse center line and terminates adjacent the geometrical center of each cover section for providing an opening in the top and bottom of each of the containers, the top opening providing an inspection slot for viewing the contents of the container, and the bottom opening providing means for locating and positioning the end of the outer course of the ball of twine.

10 With the above and other objects in view that will hereinafter appear, the nature of the invention will be more clearly understood by reference to the following detailed description, the appended claimed subject matter and the several views illustrated in the accompanying drawings.

In the drawings:

FIGURE 1 is a perspective view of the present invention and illustrates a pair of upright tubular containers which are joined together by a unitary closure cap.

20 FIGURE 2 is a fragmentary perspective view, similar to FIGURE 1, and illustrates the manner in which a removable section of the closure cap is torn therefrom so as to separate the containers from each other and to reveal the contents contained therein.

FIGURE 3 is an enlarged vertical sectional view, taken on line 3—3 of FIGURE 1, and illustrates the tubular members as being constructed of corrugated board having the corrugated flutes thereof disposed horizontally.

25 FIGURE 4 is an enlarged horizontal sectional view, taken on line 4—4 of FIGURE 1, showing the construction of the upright tubular members and illustrating the outline of a removable section in the bottom closure cap.

30 FIGURE 5 is a plan view of the inside surface of a closure cap prior to slitting and creasing thereof and shows a reinforcing tape having the fibers thereof extending diagonally across a transverse center line of the closure cap.

35 FIGURE 6 is a plan view of a two-piece blank for forming one tubular member and one closure cap in accordance with the present invention.

Referring to the drawings in detail, there is illustrated in FIGURE 1 a package, generally indicated by the numeral 10, which package includes a pair of upright tubular members 11 and 12 for forming a pair of containers 13 and 14. The containers 13 and 14 are closed at the top end thereof by an upper closure cap, generally indicated by the numeral 15, while the bottom end of the containers 13 and 14 are closed by an identical closure cap, generally indicated by the numeral 16.

40 The tubular members 11 and 12 are identical to each other and are constructed from a blank, generally indicated by the numeral 20, as is shown in FIGURE 6.

45 The blank 20 is rectangular and is provided with a plurality of parallel fold lines each extending the full width of the blank and spaced so as to define a plurality of center panels 21, an end panel 22 and a glue flap 23. As is shown in FIGURE 6, it is preferable that the end panel 22 be slightly less in width than each of the panels 21.

50 Prior to erecting the blank 20 to form a tubular member 11 or 12, it is desirable to crush the glue flap 23 and a like area of the end panel 22 such that when the glue flap 23 is adhesively secured to the end panel 22 a smooth joint is formed as is shown at 24 in FIGURE 4. The blank 20 may be cut from paperboard, heavy paper, plastic or other similar flexible material, but it is preferred that the blank 20 be formed of corrugated cardboard having the flutes 25 aligned horizontally, 55 as is shown in FIGURE 3.

60 The closure caps 15 and 16 are formed from a blank 26, as is shown in FIGURE 5. Before any printing or

die-cutting is performed on the blank 26, a reinforcing tape 27 is secured centrally thereof. The tape 27 preferably has fibers 28 which run diagonally in two directions. After the reinforcing tape 27 has been applied, the blank 26 is cut and scored, as is shown in FIGURE 16, to provide a first cover section 29 and a second cover section 30. Each of the cover sections 29 and 30 is provided along the periphery thereof with a plurality of tabs 31 which are attached along respective fold lines 32. The blank 26 is partially severed along its transverse center line by severance lines 33 and 34, tabs not being shown. The blank 26 is provided with a removable section 36 which extends on opposite sides of the transverse center line and terminates adjacent the geometrical center of each of the cover sections 29 and 30. Opposite ends of the removable section 36 are defined by arcuate cut lines 37 and 38, and the body portion of the removable section 36 is defined by weakening lines 39 and 40 which diverge from the cut lines 37 and 38 so as to meet at the transverse center line at the innermost ends of the severance lines 33 and 34.

The containers 13 and 14 which make up the package 10, as is shown in FIGURE 1, may be separated from each other by removing the removable section 36 from the upper closure cap 15, in the manner illustrated in FIGURES 2 and 3, and by removing the corresponding removable section 36 from the lower closure cap 16. It will be apparent from a consideration of FIGURES 5 and 6 that the length of the reinforcing tape 27 and the diagonal alignment of the fibers 28 thereof provide protection against inadvertent separation of the containers 13 and 14, while the narrow width of the tape 27 and the general alignment of the weakening lines 39 and 40 with the fibers 28 provide for easy removal of the section 36 from the cover sections 29 and 30. A ball of baling twine or cord 50 is disposed in each of the containers 13 and 14. Each of the balls of twine 50 is wound so as to provide a leading end 51 and a trailing end 52. When the balls of twine 50 are used with a conventional baling machine, it is the general practice to thread the leading end 51 into the baling machine such that the innermost courses of twine are used first. Also, in order to provide for uninterrupted use of the baling machine, it is the usual practice to attach the trailing end 52 of a first ball of twine to the leading end of another ball of twine which is held in reserve. When the removable section 36 is torn from each of the closure caps 15 and 16, the containers 13 and 14 are separated from each other, as is described above, and in addition, a slot 55 is formed in each of the cover sections 29 and 30. The slot 55 in the top of each of the containers 13 and 14 provides access to the leading end 51 of the twine therein and also provides an inspection slot for viewing the remaining amount of twine.

When the removable section 35, of the lower closure cap 16, is removed therefrom, the resulting slot 55 provides access to the trailing end 52 such that the end 52 of one ball may be attached to the leading end 51 of another ball of the twine. It is apparent that if the trailing end 52 is not in alignment with the slot 55, the ball of twine 50 may be manually rotated if necessary.

It will be apparent from the foregoing that there has been disclosed a unitized package which comprises a plurality of containers which are held together by upper and lower closure caps, each of which includes a removable section, the removal of which will separate the package into a plurality of separate containers.

While preferred forms and arrangement of parts have been shown in illustrating the invention, it is to be clearly understood that various changes in details and arrangement of parts may be made without departing from the spirit and scope of the invention as defined in the appended claimed subject matter.

I claim: 1. A closure cap adapted to cover an adjacent pair of

containers, said cap comprising a first cover section and a second cover section, said first cover section and said second cover section being joined along a transverse center line extending across the width of said closure cap, connecting means attached to said closure cap along the periphery thereof for connecting said closure cap to said containers, and a removable section, said removable section having opposite ends thereof located adjacent to the geometrical center of each of said cover sections, said removable section being defined by weakening lines extending from each of said opposite ends and terminating adjacent the ends of said transverse center line, said connecting means being disjoined adjacent the ends of said transverse center line, whereby separation of said removable section from said closure cap along said weakening lines detaches said first cover section from said second cover section.

2. A closure cap as defined in claim 1 including a reinforcing tape extending on opposite sides of said transverse center line, said tape having fibers extending diagonally of said transverse center line in at least two directions.

3. In combination, a pair of containers and closure caps therefor, each said container comprising an upright tubular member having at least one flat wall surface, the flat wall surface of one container being disposed adjacent to the flat wall surface of the other container, at least one of said closure caps comprising a pair of cover sections for closing said tubular members, said cover sections being substantially symmetrical about and joined together along a transverse center line at a reduced width portion of the respective closure cap, said transverse center line being disposed above and extending substantially parallel to the said flat wall surface of each of said containers, said one of said closure caps having a removable section extending longitudinally thereof on opposite sides of said transverse center line and terminating adjacent the geometrical center of each cover section, said removable section extending across substantially the entire reduced width portion of the respective closure cap whereby said cover sections are readily separable after removal of said removable section.

4. The combination as defined in claim 3 wherein, said one closure cap is provided with a reinforcing tape extending on opposite sides of said transverse center line, said tape having fibers extending diagonally of said transverse center line in at least two directions.

5. A blank for a closure cap adapted to cover ends of a pair of adjacent containers, said blank comprising a first cover section and a second cover section joined together along a transverse center line, a plurality of tabs attached to the first and second cover sections along the peripheries thereof, said first and second cover sections being reduced in width along said transverse center line, said first and second cover sections including a removable section, said removable section having opposite end portions located adjacent to the geometrical center of the associated cover section and being set-off by a weakening line extending from the opposite ends of said transverse center line toward the respective opposite end portions of said removable section.
